UNITED STATES PATENT OFFICE.

LEVI D. YORK, OF PORTSMOUTH, OHIO, ASSIGNOR TO THE YORK MANUFACTURING COMPANY, OF OHIO.

RUNNER FOR SCRAPERS.

SPECIFICATION forming part of Letters Patent No. 295,892, dated March 25, 1884.

Application filed September 10, 1883. (No model.)

To all whom it may concern:

Be it known that I, LEVI D. YORK, of Portsmouth, Scioto county, in the State of Ohio, have invented certain new and useful Improvements relating to Runners for Scrapers, of which the following is a specification.

My invention applies to what are known as "road-scrapers," "earth-scrapers," "excavators," &c., in each of which is employed a flat-bottomed or nearly flat-bottomed scoop, of thin steel or other material which it is desirable to protect from excessive wear. It has long been common to provide such with longitudinal runners, either at the edges or fixed at any given distance inward from the edges under the bottom. It is common to make such runners from square bars of iron or steel. It is frequently required in the use of scrapers to move the scraper more or less sidewise. The perpendicular sides of the ordinary runners oppose more resistance to such motion than is desirable, but it is absolutely essential to have a reasonable amount of width for the bearing at the bottom, and to produce the ordinary solid runners with inclined sides would involve a considerable addition to the weight. I employ hollow runners, of a trough-shaped section, with the bottom of sufficient thickness to withstand long wear, and with the sides flared to an angle of thirty degrees, more or less, from the vertical. My hollow runners are secured by rivets having conical heads at their lower ends. These conical heads are set in correspondingly conical recesses in the bottom of the runner. The metal around these recesses is drawn upward to a sufficient extent to make those points in the runner the last parts to wear through; consequently my rivets are held firmly by their conical heads until the runner has been rendered worthless by wearing out at other points.

The following is a description of what I consider the best means of carrying out the invention.

The accompanying drawings form a part of this specification.

Figure 1 is a side elevation, and Fig. 2 a cross-section showing the entire scraper. Figs. 3 and 4 show small portions on a larger scale. Fig. 3 is a transverse section through one of the runners and that portion of the

bottom immediately adjacent. Fig. 4 is a longitudinal section through the same parts.

Similar letters of reference indicate corresponding parts in all the figures.

A is the body of a scraper formed of sheet steel of proper thickness, preferably in the manner set forth in the patent to me dated December 27, 1881, No. 251,683. The front edge is somewhat thin or sharpened.

B B' are rivets, firmly set in the bottom, by the aid of which the runners are secured.

Each entire runner is marked D, certain portions being designated, when necessary, by additional marks, as D' D''. By the employment of suitably shaped rollers they are produced in a hollowed or channeled form, with the sides D' standing at an angle of about one hundred and twenty degrees with the bottom D''. I reduce the depth of the front end of each runner, and also to some extent the depth of the back end, thus giving a sledge-like action, as the runner impresses its shape more or less into the hard earth over which the scraper is moved.

The body of each rivet is marked B. The lower end has a deep conical head, B'. The holes in the thick bottom of the runner are correspondingly tapered, to receive the heads B', and are preferably formed by punching over a suitably-hollowed die while the steel is hot, thus not simply cutting out but forcing up the metal and raising it on the interior of the runner. The effect is to afford a long bearing on the rivet, which holds reliably after a considerable portion of the thickness of the bottom has been worn off. The upper end, B'', of each rivet may be produced by ordinary means after the insertion of the rivet, and may usually project somewhat above the upper surface of the bottom of the scraper A without serious objection.

Whether the rivets are inserted hot or cold, it is easy to confine the hollow runners strongly and firmly. The elasticity of the runner, due to its hollow form and flared sides, as thus forcibly held up by these rivets, contributes to maintain a tight, firm joint under all conditions. The runners form a unit with the body both for contributing to its rigidity and yielding to its elasticity. Their inclined sides allow the scraper to be moved laterally to small extents, and to be swiveled.

around in steering and in the various manipulations required in the exigencies of rough work. Scrapers with my runners are lighter than ordinary scrapers having the same breadth and depth of runners.

When scrapers with ordinary runners are worked in adhesive soil, the material is liable to stick in the angle on each side of the runner. My runners, by reason of the inclinations of their sides, present less facility for such accumulation.

Modifications may be made in the forms and proportions within wide limits. The rivets may be set nearer together or wider apart. 15 The tension of the rivets tends to draw up the base of the runner at each point where a rivet is inserted, and even if no care is taken to raise the metal adjacent to the hole, the tension induces this effect to a sufficient degree to make 20 those points the last to wear out. The hollow

runners are thus sure to be held by the conical rivets until they commence to be worn through at other points, when they must be removed and new ones substituted.

I claim as my invention—

25

1. The hollowed runners for scrapers herein described, having a thick bottom, D², with inclined sides D', adapted to serve as herein specified.

2. A scraper having hollow runners D' D², 30 applied and secured substantially as herein specified.

In testimony whereof I have hereunto set my hand, at Portsmouth, Ohio, this 28th day of August, 1883, in the presence of two subscribing witnesses.

LEVI D. YORK.
